UNITED STATES PATENT OFFICE

167,410

LAWN MOWER HEAD UNIT

Julia A. Laughlin, St. Petersburg, Fla.

Application September 12, 1951, Serial No. 16,615

Term of patent 14 years

(Cl. D40—1)

To all whom it may concern:

Be it known that I, Julia A. Laughlin, a citizen of the United States, residing at St. Petersburg, in the county of Pinellas and State of Florida, have invented a new, original, and ornamental Design for Lawn Mower Head Unit, of which the following is a specification, reference being had to the accompany drawing, forming a part thereof.

Fig. 1 is a top view of a lawn mower head unit embodying my new design.

Fig. 2 is a side view of the lawn mower head unit of Fig. 1.

Fig. 3 is a perspective view of the lawn mower head unit.

I claim:

The ornamental design for a lawn mower head unit, as shown.

JULIA A. LAUGHLIN.
